UNITED STATES PATENT OFFICE

173,183

HAT

Stephen C. Boneau, Atchison, Kans.

Application January 14, 1954, Serial No. 28,513

Term of patent 7 years

(Cl. D3—13)

To all whom it may concern:

Be it known that I, Stephen C. Boneau, a citizen of the United States, residing at Atchison, State of Kansas, have invented a new, original, and ornamental Design for a Hat, of which the following is a specification, reference being had to the accompanying drawing, forming part thereof, in which:

Fig. 1 is a front perspective view of a hat embodying my new design, and

Fig. 2 is a rear perspective view of same.

I claim:

The ornamental design for a hat, substantially as shown.
